UNITED STATES PATENT OFFICE

155,745

DESIGN FOR A BICYCLE

Clifford Brooks Stevens, Milwaukee, Wis., assignor to The Cleveland Welding Company, a corporation of Ohio

Application August 25, 1948, Serial No. 148,286

Term of patent 3½ years

(Cl. D90—8)

To all whom it may concern:

Be it known that I, Clifford Brooks Stevens, a citizen of the United States, and a resident of Milwaukee, county of Milwaukee, and State of Wisconsin, have invented a new, original, and ornamental Design for Bicycle, of which the following is a specification, as a continuation-in-part of my application Serial No. D. 126,461, filed February 11, 1946, now abandoned, reference being had to the accompanying drawing, forming a part thereof.

In said annexed drawing, the single figure is a perspective view of a bicycle showing my new design, the opposite side presenting substantially the same appearance as the side shown.

I claim:

The ornamental design for a bicycle, as shown and described.

CLIFFORD BROOKS STEVENS.
